Japan

Filed Aug. 16, 1961, Ser. No. 131,855
Claims priority, application Japan Feb. 28, 1961
4 Claims. (Cl. 222—3)

The present invention relates to a cigarette lighter using liquefied combustible gas as fuel wherein the quantity of discharge flow of the liquefied gas in a tank from a burner is adapted to be controlled by moving axially up and down a hollow movable valve member being formed at its upper end with the burner thereof.

In the gas lighter referred to above, generally, a hollow movable valve member is screw threaded in the inner periphery of a blinded cylindrical sleeve extending with its bottom portion into the tank, and the upper part of the hollow movable valve member projecting upwardly beyond the opening of the cylindrical sleeve. An operating ring is attached on the valve member by means of a spring washer or the like. By turning the operating ring, the movable valve member is moved up and down within the sleeve. Accordingly, a venting member consisting of a resilient pad member contained at the bottom portion of the sleeve is compressed or is released from the pressure thereof, so as to control the quantity of discharge flow of gas through the movable valve member. For such means, the operating ring is moved up and down accompanied with the up and down movement of the movable valve member. However, owing to the position of this operating ring on the end of the tank, when the upward movement of the movable valve member is effected for increasing a flux of gas by releasing the pressure of the ventilating member, the operating ring produces an unpleasant noise due to play in an upward and a downward direction between the tank and the spring washer which is attached to the movable valve member to avoid the upward removement of the operating ring. Also, when the movable valve member is lowered for reducing the flux of gas, the operating ring is in contact with the wall of the tank, and finally the operating ring cannot be turned for a further lowering movement of the movable valve member.

In such a form, a part of periphery of the operating ring may be overhung outwardly to form a stopper. In such case, the operating ring may be operated in such a manner that it cannot be turned except within a range of impacting with the front end of a wall of a bearing provided on both sides of the wall of the tank. However, in such a case, the allowable capacity for turning of the operating ring, determined by the stopper and the wall of the bearing is not attained for one revolution, and consequently the control range for discharge gas flux is limited to a small range and it cannot be controlled above that limited range.

It is, therefore, one object of the present invention to provide a cigarette lighter which avoids the disadvantages of the known apparatus. It is another object of the present invention to provide a construction of a cigarette lighter in which even when the allowable capacity for turning the operating ring is determined, the movable valve member is adapted to be moved above the limited range so as to control freely the discharge of the gas flux. Incidentally, even upon moving upwardly the movable valve member, the operating ring does not engage the wall of the tank, and also even upon lowering the movable valve member, the operating ring is not urged strongly against the wall of the tank to such a degree, that it cannot be turned.

2

With these and other objects in view, which will become apparent in the following detailed description, the present invention will be clearly understood in connection with the accompanying drawings, in which:

5 FIG. 1 is a longitudinal sectional view of the flux control device of the gas lighter,

FIG. 2 is a longitudinal sectional view similar to that shown in FIG. 1, yet in a different working position,

FIG. 3 is a top plan view of the device shown in FIG.

10 1, parts being broken away for better demonstration,

FIG. 4 is a longitudinal sectional view of an essential part of a gas lighter disclosing another embodiment thereof,

FIGS. 5 and 6 are longitudinal sectional views of the 15 embodiment shown in FIG. 4 in different operative positions,

FIG. 7 is a top plan view, partly broken away, of the embodiment disclosed in FIG. 4,

FIG. 8 is a longitudinal sectional view of an essential 20 part of a gas lighter, disclosing a third embodiment thereof,

FIGS. 9 and 10 are longitudinal sectional views of the embodiment shown in FIG. 8, in different operative positions thereof; and

FIG. 11 is a top plan view of the embodiment shown in 25 FIG. 8.

Referring now to the drawings, and in particular to the embodiment shown in FIGS. 1 to 3, a tank *a* contains compressed and liquified combustible gas. A valve cylinder *b* is fitted at its open end to the wall of the tank *a* and projected into the tank *a* at its major part. A movable valve member screw *c* is threaded into the inner periphery of the valve cylinder *b*. A through hole 1 is disposed at the bottom face of the valve cylinder *b* to provide a communication with the tank *a*. A resilient member 2 having a central hole 2_a, which is aligned with the hole 1, is received in the valve cylinder *b*. A passage 3 is disposed in axial direction in the movable valve member *c*, and the upper end opening of the passage 3 forms a burner 4. Thus, when the movable valve member *c* is turned, the resilient member 2 is compressed by the lower end of the movable valve member *c* to reduce the diameter of the hole 2_a, or when the pressure upon the resilient member 2 by the valve member *c* is released, the inner open diameter of the hole 2_a is restored to its original shape. Accordingly, the discharge gas flux injecting at the burner 4 through the central hole 3 is suitably controlled.

On a peripheral part of the movable valve member *c* projecting from the open end of the valve cylinder *b*, splines 5 are formed longitudinally. An operating ring *d* has at its central part of the bottom of a recessed part 6 splines 7, disposed in a central hole thereof and in engagement with the splines 5 of the valve member *c*. Consequently, when the operating ring *d* is brought into engagement from the side of the burner 4 with the movable valve member *c* and also brings about engagement of the splines 7 with the splines 5, the injecting gas quantity can be adjusted through the operating ring *d* by the movable valve member *c*. A pawl 8 is formed on the operating ring *d* by cutting and bending outwardly along its downward peripheral wall.

The operating ring *d* can be turned within a range impacting the pawl 8 with the side wall *f* of a bearing of 60 a burner cover *e* provided on tank *a*.

A coil spring 9 is contained in the recessed part 6 and the coil spring 9 is prevented from a further lifting or falling off by means of a washer 11 and a washer spring 10 which is mounted on an upper part of the movable valve member *c*. The washer 11 supports the upper part of the coil spring 9 in its compressed state. In this state, the operating ring *d* is lowered until its downward pe-

peripheral wall is in contact with the upper part of the tank *a*, or until the bottom surface of the recessed part *6* engages the upper end of the valve cylinder *b*, and the spline *7* are held in engaging relation with the splines *5*. Preferably, the washer *11* is dimensioned such as to enter slightly into the recessed part *6* and the spring washer *10* serves to hold the washer *11* at the same level as the upper surface of the recessed part *6*, so as to improve the external appearance of all the parts. The other end of the coil spring *9* engages the outer bottom surface of the 10 recessed part *6*.

The operating ring *d* can be turned freely without engaging the movable valve member *c*, when the splines *7* are released from the splines *5*, by lifting the operating ring *d*, so as to compress the coil spring *9* as shown in 15 FIG. 2.

In accordance with the present invention, the operating ring *d* is always held by means of the coil spring *9* to engage the movable valve member *c*, and consequently any play on the operating ring *d* or any heavy turning of the 20 operating ring *d* can be eliminated entirely, notwithstanding the ascent and descent of the movable valve member *c*. It is to be noted that the above fact is a true matter in either case of using a freely turnable operating ring or using a definite range turnable operating ring, especially in the latter case the operating ring may be turned by lifting once the operating ring against the action of the coil spring so as to release it from the engagement with the movable valve member and then by lowering it to obtain a fresh engagement with the movable valve member. In such latter case, the movable valve member of course can be turned over a limited definite range.

Referring now again to the drawings, and in particular to the embodiment shown in FIGS. 4 to 7, a tank *a'* contains compressed and liquefied combustible gas. A valve cylinder *b'* is fitted at its open end to the wall of the tank *a'* and projects into the tank *a'* at its major part. A movable valve member screw *c'* threaded into the inner periphery of the valve cylinder *b'* is attached thereto in axial direction. A through hole *1* is provided at the bottom face of the valve cylinder *b'* in communication with the tank *a'*. A resilient member *2'* having a central hole *2a'* which is aligned with the hole *1* is received in the valve cylinder *b'*. A passage *3'* is provided in axial direction in the movable valve member *c'*, and the upper end of the passage *3'* forms a burner *4'*. Thus, when the movable valve member *c'* is turned, the resilient member *2'* is compressed by the lower end of the movable valve member *c'* to reduce the open diameter of the hole *2a'*, or when the compression of the resilient member *2'* by the valve member *c'* is released, the open diameter of the hole *2a'* is restored to its original size. Accordingly, the discharge gas flux injecting at the burner *4'* through the central hole *3'* is suitably controlled.

On a peripheral part of the movable valve member *c'* projecting from the open end of the valve cylinder *b'*, splines *5'* are formed longitudinally. An operating ring *d'* has at its central part a recessed part *6'*. At the central part of the bottom of the recessed part *6'*, splines *7'* form a hole and engage the splines *5'*, and consequently when the operating ring *d'* is inserted from the side of the burner *4'* over the movable valve member *c'* an engagement is brought about of the splines *7'* with the splines *5'*, the injecting gas quantity can be adjusted through the operating ring *d'* by the movable valve member *c'*. A pawl *8'* is formed from the operating ring *d'*, by cutting and bending outwardly along its downward peripheral wall.

The operating ring *d'* can be turned within a range impacting the pawl *8'* with the side wall *f'* of a bearing of a 70 burner cover *e'* provided on the tank *a'*.

An annular groove *9a'* is formed on the upper periphery of the movable valve member *c'* so as to engage a washer *10'* which is broken away a part of its periphery, and, thereby, the falling off of a washer *11'* fitted to the mov-

able valve member *c'* is prevented. A fitting cavity *12'* for embedding the washer *10'* is formed in the washer *11'*. The washer *10'* is fitted in the fitting cavity *12'* in such manner that the washer *11'* is pressed upwardly by means of a coil spring *9'* and splines *7'* formed in the hole of the bottom part of the operating ring *d'* engage the splines *5'* formed on the movable valve member *c'*. Further, the external periphery of the washer *11'* is formed with a downward skirt *11a'*, and consequently the washer *11'* can be moved axially in the recessed part *6'* of the operating ring *d'* without distortion.

As this embodiment is constructed as above described, the movable valve member *c'* can be turned over a definite limit in which the pawl *8'* of the operating ring *d'* impacts with a side wall *f'* of a bearing for controlling the discharge gas flux injecting from the burner *4'*. In such a case, as shown in FIG. 6, the operating ring *d'* is lifted against the action of the spring *9'*, so as to release the engagement of the splines *7'* and *5'*, and the operating ring *d'* can be turned freely relative to the movable valve member *c'*. Thus, when the operating ring *d'* is released, to be restored into its original position, the operating ring *d'* is lowered by the extending action of the coil spring *9'* and the splines *7'* engage the splines *5'*, and consequently the discharge gas flux can be adjusted over the definite limitation by a further turning of the operating ring. Further, in this assembling, the operating ring *d'*, the coil spring *9'* and the washer *11'* are inserted and fitted from the side of the burner *4'* into this lighter in the order as above mentioned and then the washer *11'* is forced into the recessed part *6'*, so as to compress the coil spring *9'*, and, thereafter, the washer *10'* may be fitted into the annular groove *9a'*. The above assembly of all the parts is effected in a very simple manner. Thus, as the attached washer *10'* is fitted firmly in the fitting groove *12'*, the washer *10'* does not fall off entirely. Further, if any difficulty in the operation arises, or when cleaning is necessary, the reverse operation of the above assembling operation may be effected very easily.

Referring now again to the drawing, and in particular to the embodiment shown in FIGS. 8 to 11, splines *5²* and splines *7²* are formed, respectively, on an inner central hole of the operating ring *d²* and on the outer periphery of the washer *11²*. Accordingly, when the operating ring *d²* is turned in a predetermined direction, the movable valve member *c²* is moved in axial direction. Other parts of this embodiment are the same as those shown in the first and second embodiments, and the operation of the third embodiment is substantially the same. Accordingly, the same numerals with an index 2 have been applied to the corresponding elements.

While we have disclosed three embodiments of the present invention, it is to be understood that these embodiments are given by example only and not in a limiting sense, the scope of the present invention being determined by the objects and the claims.

What we claim is:

1. A cigarette lighter comprising a tank adapted to receive compressed and liquefied combustible gas, a hollow valve cylinder immovably mounted in said tank and having a bottom and threaded internally, a valve member having an outer thread engaging said inner thread of said hollow valve cylinder and being axially movable in said hollow valve cylinder upon relative rotation between said hollow valve cylinder and said valve member, said valve member projecting outwardly from said valve cylinder and having a first axial discharge bore extending along the entire length of said valve member, a resilient member embedded in the bottom of said valve cylinder and having a second axial discharge bore aligned with said first discharge bore, said bottom of said hollow valve cylinder having a

third axial discharge bore aligned with said second axial discharge bore,
 an operating ring having a recess defining a bottom wall and a cylindrical wall and being open at its top and having an opening in its bottom to surround the outer portion of said valve member,
 said valve member including a washer disposed at its upper portion and having a first spline and said operating ring having a second spline engaging said first spline of said valve member,
 a coil spring disposed in said recess between said bottom wall of said operating ring and said washer and tending to move said operating ring into engagement with said valve member,
 said operating ring being freely turnable upon disengagement of said second spline from said first spline of said valve member,
 means preventing said washer from being pushed off said valve member, and
 said valve member controlling the discharge flow of 20 said liquefied combustible gas by turning said operating ring.
 2. The valve, as set forth in claim 1, wherein
 said means preventing said washer from being pushed off said valve member comprises

15
10
20
25

a washer spring disposed on the opposite side of said washer from said spring, and
 said valve member has an annular outer groove in its upper portion receiving said washer spring.
 3. The valve, as set forth in claim 1, wherein
 said second spline of said operating ring is disposed at said opening of the bottom of the latter.
 4. The valve, as set forth in claim 1, wherein
 said second spline of said operating ring is disposed at the inner face of said cylindrical wall, and
 said washer is keyed to said valve member to rotate jointly with the latter and to perform an axial movement relative to the latter.
